UNITED STATES PATENT OFFICE.

JOHN RINNE, OF RUTLEDGE, PENNSYLVANIA.

METAL FRAMEWORK FOR UMBRELLAS.

Application filed September 21, 1925. Serial No. 57,676.

This invention relates to a framework, for umbrellas, parasols and other rain or sunshades in which the rib rods and handle rods are composed of small cross linkage, and in 5 which the ribrod linkage is connected to handle rod linkage in such a way that both of them move in unison and the whole unit can be closed to a very compact form and again quickly opened or extended to the umbrella form for use. Further objects and 10 advantages of the invention will be set forth in detail description which follows:

In the accompanying drawing, Figure 1, is a vertical sectional view of handle rod and 15 one ribrod in extended or open position with a section of the former broken off to save space, and a part of the latter shown in a separate view.

Figure 2 shows the broken off extension to 20 the ribrod shown in Figure 1.

Figure 3 is a side elevation showing handle rod linkage and guide tube in extended or open position of which the upper end is cut off.

25 Figure 4 is a sectional elevation showing the framework folded together in closed position.

Figure 5 is a sectional plan view of framework when closed.

30 Figure 6 is a part section through the upper end of the handle rod showing its linkage connection to rib linkage, also showing small auxiliary linkage in connection with one pair of ribrods base links.

35 Figure 7 is a side elevation of pivot plates showing relative position of slots for base links when frame is open.

The framework is indicated generally 40 showing only one of the ribrods, the other rods being omitted for the sake of clearness. It will be understood that there are several ribs located radially around the handle rod, which are of the same construction as the one shown to form the complete framework 45 for the cover. This complete framework is made of metal, preferably strong aluminum alloy, or other non-corroding metal.

The handle rod shown in Figures 1 and 3 50 consists of small narrow bars 1, 2, 3 and 4 which are connected in pairs at the center, and fastened to each other by a rivet 5. There are four bars two of which, 2 and 3, are heavier in the middle and two thinner, 1 and 4, on the outside, all forming a double 55 cross linkage to give the handle rod required stiffness and strength. These cross links are

connected at each end to other similar linkage units by rivets, 7 and 8, to form, when extended, a straight rod or center post. To the last links, 9 and 10, at the end of the rod a 60 handle is fastened which consists of two half round pieces, 11 and 12, which while in a position opposite each other when the complete mechanism is in the extended or open position, form a convenient handle. At the cross 65 point 13, the handle rod linkage is fastened to a short tube 14 by a rivet through the filler pieces 15 and 16. This tube has slots through 70 its sides and opposite each other extending nearly the whole of its length to allow links 17, 18, 19 and 20 to fold out at their connection joints 21 and 22. Links 19 and 20, which are only single bars and half length links, are in their joint, 23, fastened to a pin, 24. This pin has a head at its lower 75 end with a slot, 25, for fitting the links, and the pin itself acts as a stiffening guide for handle rod and also forms the tip for the umbrella, when the framework is open.

To allow the pin to slide freely in the tube, 80 the heavier end is slightly smaller than the inner diameter of the tube, and the thinner or upper part slides in the upper pivot plate. The pin head is fastened by a through pin, 85 26, to the lower pivot plate, 27, which slides up and down on the outer surface of tube, 14. The ribrods are of similar construction as handle rod with a similar joint spacing, but are composed only of single cross linkage. At the base of the ribrod the link, 31, is 90 fastened to the lower pivot plate, 27, by a pivot ring, 29, which is sunk in a groove in the plate, as shown in dotted lines, 30, Figure 5.

In the pivot plate 27 are radial slots 95 extending through the pivot grooves to the depth of half width of the link to form a space for inserted link end. This groove is open at the top to allow the link to turn freely upwards. To this lower pivot plate is fastened a flange, 28, to form a hand hold for closing and opening purposes.

The upper pivot plate, 49, is of similar construction as the lower and is fastened to the upper end of the guide tube 14. It has a hole 100 through the center to allow pin, 24, to slide back and forth. To this pivot plate is fastened the link, 32, in the same manner as link, 31, is to the lower plate, 27, by a pivot ring, 33, through a hole in the end of the link. 110 These base links, as all other links are connected to each other in pairs, by pivot rivets,

34. Of these link bars the links in the first and second pairs, are of equal width, but then the bars in each pair gradually are made narrower between the ends and center as shown in, Figures 1 and 2, to allow the whole ribrod flexibility for bending, when extended and to reduce the weight. The last pair is composed of one half length link, 35, Figure 2 and a narrow long link, 36, this longer link has at its free end a small hole, 37, for fastening the edge of the cloth covering.

5 10 15 20 25 30 35 40 45 50 55 60 65 All the linkage joints are formed by small pins or rivets, and to allow the links freedom to move, there are at all joints, the rivet washers, under the rivet heads, 43 Figure 6. In the ribrods at upper connection points, in addition to the outside washers, there is a washer, 39, Figure 6, between the link ends, that is free to turn on the pin, and it has in the outside extension a small hole, 38, for fastening the cover cloth at each joint, and to allow it to locate itself when being stretched.

This cloth is fastened at the center around the tip, 24, Figure 6, by a round thin washer, 41, the cloth being held between the washer and upper pivot plate, these being fastened to each other, by screws or rivets.

To allow the required curvature to the ribrods, which would otherwise throughout the whole extending motion form, a very rigid straight frame, the holes in links at their lower connections, 42, Figure 6, are slightly oblong, to allow the link ends to slide a little towards each other on the pivot pin, the outside washers acting as guides.

40 45 50 55 60 65 To open the frame, when it is closed as shown in, Figure 4, is very simple. The center part of the handle is held between the fingers, and while rib links are hanging downward, the whole unit is twisted with a slight sudden jerk. The centrifugal force causes the ribrods to move out, which motion is continued, by pulling the handle and pushing against the plate, 28. Through this movement the handle rod and ribrods stretch out simultaneously. When wide open, the whole frame work is interlocking, which is caused by curvature in ribs when cloth cover is tightened.

50 55 60 65 The closing movement is actuated, by pushing the handle and flange 28 towards each other. This causes all the links in both handle rods and ribrods to move to a position shown in, Figure 4. The rigidity to ribs at the root when framework is open is given by the part of the pivot plates, which surround the link ends, when the both plates come together and slots, 44, Figure 7, in one plate pass the slots in the other. These slots are not spaced in equal distances radially, the spaces being largest, which are farthest away from the handle, when frame is closed. This is to lessen the sideway bending of the collapsed rib linkage in the closed frame, and to make the whole unit narrower, when put in the

final umbrella case, in which it may be carried. The cloth covering will fold on outside of framework, when umbrella is closed, as shown partially, 40, Figure 6, so that it does not interfere with frame linkage. To allow 70 more freedom to the farthest rib units, for side turning there can be added, if necessary, short auxiliary links, 46, Figure 6, to the ends of base links, which are in that case cut shorter, with the ends bent outward as shown in, 75 Figure 6. These auxiliary links are fastened to the pivot plate in the usual way, but have in their outer ends a ring of round cross section, which goes through the slot, 48, in link end, as shown in the drawing. The eye rings, 80 which are turned on an angle act as on hinges, on which the rib is able to turn to a position nearly parallel with handle, when frame is closed.

85 It is understood that the invention is not limited to the precise construction as here set forth, but that it includes within its extent the construction forms, which fairly come within the terms of the following claims.

Having described my invention, what I 90 claim as my invention is:

1. The combination of an umbrella framework comprising a staff, said staff composed of a series of collapsible cross links pivotally connected together, a plurality of ribs of 95 similar construction, means connecting said staff and ribs to permit said staff and ribs to collapse simultaneously.

2. In a framework for an umbrella or the like, the combination of a staff or handle rod composed of a series of collapsible cross links, a sliding guide pin at the end of said staff, and a plurality of ribs each composed of a series of collapsible cross links, one link of each rib being pivoted to the sliding guide 100 pin, said guide pin acting as a tip for the umbrella when in open position.

3. In a framework for an umbrella or the like, the combination of a staff or handle rod composed of a series of collapsible cross links pivotally connected together, a plurality of collapsible ribs connected to one end of said staff, and a pair of sectional handle pieces carried by the links at the other end of the staff and forming a handle when the staff is 110 extended.

4. In a framework for an umbrella or the like, the combination of a staff or handle rod composed of a series of collapsible cross links pivotally connected together, a plurality of ribs of similar construction, means connecting the ribs to the staff, and means provided in the pivotal connections of the rib cross links 120 permitting said ribs to assume a curved form.

5. In a framework for an umbrella or the like, the combination of a staff or handle rod, a plurality of ribs composed of a series of collapsible cross links pivotally connected together, a pair of pivot plates carried by the staff and provided with radial slots in which 130

the end cross links of the ribs are pivoted, the slots of one plate being staggered or offset with respect to the slots in the other plate, whereby said slots of one plate are closed on 5 the adjacent side by the other pivot plate.

6. In a framework for an umbrella or the like, the combination of a collapsible staff or handle rod, a plurality of collapsible ribs, means for connecting the ribs to the staff, a 10 cover cloth secured to said ribs, said framework being locked in open position by the stretching of said cover cloth.

7. In a framework for an umbrella or the

like, the combination of a collapsible staff or handle rod, a plurality of ribs each composed of a series of collapsible cross links pivotally connected together, and means for connecting said ribs to said staff, said means including auxiliary links permitting the cross links to assume a position substantially 15 parallel to the staff when said ribs are collapsed.

In testimony whereof, I have hereunto subscribed my name this 18th day of September 1925.

JOHN RINNE.
